UNITED STATES PATENT OFFICE

152,475

DESIGN FOR AN ARTICLE HOLDING GUARD OR THE LIKE

Otto W. Hueter, Toledo, Ohio

Application August 10, 1948, Serial No. 148,020

Term of patent 14 years

(Cl. D14—6)

To all whom it may concern:

Be it known that I, Otto W. Hueter, a citizen of the United States of America, residing at Toledo, Lucas County, Ohio, have invented a new, original, and ornamental Design for an Article Holding Guard or the like, of which the following is a specification, reference being had to the accompanying drawings:

Fig. 1 is a perspective view of an article holding guard or the like, showing my new design;

Fig. 2 is a front elevation thereof; and

Fig. 3 is a plan view, looking down on the device of Fig. 1.

This application is a continuation-in-part of my co-pending application Ser. No. D. 140,263 filed June 14, 1947.

I claim:

The ornamental design for an article holding guard or the like, as shown and described.

OTTO W. HUETER.
